FIG. 6.

UNITED STATES PATENT OFFICE.

ABRAM R. VICKERS, OF CAMDEN, NEW JERSEY, ASSIGNOR TO CURTIS-MARTIN NEWS-PAPERS, INC., OF PHILADELPHIA, PENNSYLVANIA, A CORPORATION OF PENNSYLVANIA.

MARGIN-PRINTING MECHANISM.

Application filed January 24, 1928. Serial No. 249,009.

The present invention relates to an improved margin printing mechanism especially adapted for use as an attachment for rotary printing presses or machines of the newspaper type, and while here illustrated and adapted for use with a printing press of the well known Scott type, is also adapted for use with slight alterations on other presses of the Hoe type. The printing mechanism of the invention is adapted to be operated from the main printing press, in connection with the impression cylinder of the latter, for printing a strip along the margin of the newspaper or web. The strip may be a solid line or it may be a strip of solid matter, printed in a selected color, independently of the operation of the main printing machine, or if printed matter is used by the margin printing mechanism, such matter can be printed from an engraving on the plate roll in combination with the impression cylinder.

The invention consists in certain novel combinations and arrangements of parts forming the attachment or mechanism, together with means for moving the attachment into and out of operative position, with relation to the main printing press or to the impression cylinder thereof, and various adjusting devices are utilized for assuring efficiency and smooth operation of the mechanism of the attachment, as will hereinafter be more fully set forth and claimed.

In the accompanying drawings one complete example is illustrated of the physical embodiment of the newspaper margin printing mechanism in combination with a rotary press of the Scott type, wherein the parts are combined and arranged according to one mode for the practical application of the principles of the invention, and it will be understood that the illustrated structure may be modified with facility to adapt the printing mechanism for use on other printing presses of the rotary type and making the impression upon a newspaper, or other web.

Figure 1 is a view in side elevation, partly in section for convenience of illustration, illustrating the margin printing mechanism in operative relation to parts, including the impression cylinder, of a rotary printing press.

Figure 2 is a view in elevation of the

mechanism as seen from the right of Figure 1.

Figure 3 is an enlarged detail view showing the eccentric device for throwing the mechanism into and out of operative relation. 55

Figure 4 is a top plan view of the mechanism, an attaching bracket arm being shown 60 in section.

Figure 5 is an enlarged detail view of the adjusting device for regulating the transfer of ink from the composition roller to the plate roller. 65

Figure 6 is a view showing the cam bolt of the eccentric device for throwing the mechanism into and out of operative relation. 70

In order that the general arrangement and relation of parts may readily be understood Figure 1 discloses tie rods or cross rods 1, 2 and 3 of a Scott press of which the impression cylinder is indicated at 4. Through the instrumentality of a train of gears 5, 6, 7, and 8, operated from the main press, in suitable manner and at predetermined speed with relation to the movement of the web of paper about the cylinder, the printing mechanism is actuated to print along the margin of the moving web or newspaper. 75 80

The ink is supplied from a fountain or reservoir 9 of adequate size for the purpose, which is fastened with attaching perforated lugs 10, spaced apart and designed to fit on the tie bar or rod 3 of the main press, and caps 11 are secured to the lugs by means of clamp bolts 12, in such manner that the entire operating mechanism may be swiveled on the rod 3. Thus the mechanism is supported in such manner that the gear 6 may be brought 90 into mesh with gear 5 when the mechanism is to be operated, and the gears may be separated to render the mechanism inoperative. By means of the lugs and caps the mechanism is supported with stability on the rod and 95 devices hereinafter described, are used to swing the attachment on the rod 3 as a center.

A split collar 13, with its screws or bolts 14, is used on the rod at one end of the attachment to prevent displacement, and at the 100 other end of the attachment an attaching arm 15 is used, said arm having a pair of end lugs 16 to which the caps 17 are secured by bolts 18. Thus the whole attachment may be applied to the main press without dismantling the latter, and the attachment may 105

be clamped in place with facility and then adjusted to insure accuracy in the performance of its functions.

The ink is transferred from the reservoir or fountain 9 by means of the ink fountain roll 19, the composition roller 20 and the plate roller 21, which latter transfers the ink to the web, along its margin, as the web passes over the impression cylinder. The fountain roll 19 is located within the reservoir and projects therefrom a sufficient distance for co-operation with the composition roll 20 located outside the reservoir. The fountain roll is fixed to revolve with its shaft 22, that is journaled in the walls of the reservoir or fountain, and the gear 8 is carried by this shaft 22.

The quantity of ink carried by the ink roller 19 and transferred to the composition roller, 20 is regulated by means of a cut off or adjustable slide plate 23, supported in the top of the reservoir in line with the roll 19, and adapted to be slid toward and away from the roll for varying the quantity of ink carried on the periphery of the ink roller. This slide plate has a downturned, perforated end or flange 24 overhanging the back wall of the reservoir or fountain, and an adjusting bolt 25, passed through this perforated flange and threaded 30 into a complementary socket in the wall of the reservoir, is used to move the slide plate in or out with relation to the roller 19. By means of a lock nut 26 on the bolt and engaging the face of the reservoir, the plate may be locked in its desired adjusted position for regulating the ink carried by the ink roller 19.

The beveled-edge plate roller is supported in proper relation to the impression cylinder 4, above the reservoir or fountain and revolves 40 with its shaft 27 in bearings 28 preferably formed integral with the top of the reservoir or fountain and spaced at opposite sides thereof.

The shaft 29 for the composition roller 20 is journaled in an adjustable bearing block or slide 30 located in the guide slot 31 of the supporting arm 32. This arm has a hole 33 for the shaft 27 and a hole 34 (Fig. 5) for the bolt 35, which bolt, at its end is threaded into 50 a perforated and threaded lug 36 rigid with the reservoir. Thus the arm 32 may be swiveled on the shaft 27 and by means of the slot 34 of the arm the latter may be swung slightly of course on its pivot 27 to vary the relationship between gears 7 and 8 and rollers 19 and 20.

For adjusting the composition roller with relation to the plate roller to regulate the transfer of ink from the former to the latter, 60 a screw bolt 37 carried by the plate 32 is threaded into the slide or bearing block 30, and lock nuts 38 on the bolt are used to hold the bolt and bearing block in adjusted position.

65 The reservoir and its rollers and gears and

other parts, are adapted to be swung, through the lugs 10 and caps 11, on the tie rod 3, to bring the mechanism into or out of operative position, and for this purpose the cam bolt or eccentric bolt 39 of Figure 6 is used and 70 turned by means of a handle or lever 40 fixed on the threaded end of the eccentric bolt. The bolt is journaled to turn in a bearing boss 41 fashioned integral with the bracket arm 15, and the bolt has a cam head or eccentric 75 head 42 and concentric retaining head 43 as best seen in Figure 6. The eccentric head 42 of the bolt is located between the forks 44 of a bearing yoke or plate 45 which is attached as by bolts 45' to a portion of the reservoir 80 or fountain walls, and it will be apparent that by turning the bolt 39 through lever 40 the eccentric head 42 co-acting with its yoke 44, the mechanism may be swiveled on the tie rod 3, for the purpose described. A lock nut 85 46 on the eccentric bolt may be turned with its lever 47 to lock the mechanism in adjusted position, and a stop bolt 48 on the reservoir is set by means of the lock nut 49, to engage against a portion of the bracket arm 90 15 as a positive stop in the adjustment for pressure between the plate roll and the impression cylinder.

Having thus fully described the invention, 95 what is claimed herein is—

1. A printing attachment for rotary presses comprising an ink reservoir and means for swiveling the reservoir with relation to the rotary press, means for retaining the attachment in adjusted position, means for limiting the adjustment of said attachment, a plate roller supported on the reservoir for co-action 100 with the rotary press, and inking devices for transferring ink from the reservoir to the plate roller.

2. The combination with a rigid support forming part of a rotary printing press, of a swiveled ink-reservoir and an ink roll therein, a composition roll and a plate roll whereby the ink is transferred from the plate roller 110 to the web on the impression cylinder of the press, means for adjusting the ink-reservoir to vary the relation between the plate roller and impression cylinder, and means for limiting the adjustment of the ink-reservoir.

3. An attachment for a printing press comprising an ink-reservoir and an ink roller having its shaft journaled in the reservoir walls, a composition roller, adjustable means for regulating the quantity of ink carried by the ink roller for transfer to the composition roller, means for adjusting the composition roller with relation to the ink roller, a plate roller adapted to receive ink from the composition roller and means for adjusting the relation of the composition roller to the plate roller.

4. The combination in a printing attachment with a plate roll and its shaft, of an arm swiveled on said shaft and a composition roll-

er, a shaft for the composition roller and a bearing block for said shaft slidable in the arm, means for adjusting the slide bearing-block, and means for adjusting the swiveled 5 arm.

5. The combination with an ink reservoir an ink roller therein and a shaft for the roller journaled in the walls of the reservoir, of a slide plate in the top of the reservoir for 10 regulating the quantity of ink carried on the

periphery of the roller, a screw bolt for sliding the plate, a plate roller and its shaft journaled above the reservoir, a plate having a swivel support on the last mentioned shaft, a slide bearing block carried by the plate and 15 means for adjusting said block, a composition roller having its shaft in said block, and means for adjusting the swiveled plate.

In testimony whereof I affix my signature.

ABRAM R. VICKERS.
